FLY SWATTER

Filed May 15, 1922

2 Sheets-Sheet 2

Fig. 3.

UNITED STATES PATENT OFFICE.

LEWIS B. McDANIEL, OF LA BELLE, MISSOURI.

FLY SWATTER.

Application filed May 15, 1922. Serial No. 560,948.

To all whom it may concern:

Be it known that I, LEWIS B. McDANIEL, a citizen of the United States, residing at La Belle, in the county of Lewis and State 5 of Missouri, have invented a new and useful Fly Swatter, of which the following is a specification.

The device forming the subject matter of this application is an attachment for a screen 10 door. The device includes a pair of wings, normally disposed parallel to the door, when the door is closed, and the invention aims so to construct the wings and so to operate them that, when the door is opened the flies 15 will be caught between the wings and crushed therebetween, the wings ultimately returning to a position parallel to the door.

Figure 1 shows in plan, a device constructed in accordance with the invention; Figure 20 2 is a fragmental section taken in a plane at right angles to the door; Figure 3 is a top plan; Figure 4 is a section taken through the releasable catch; Figure 5 is a sectional detail showing a portion of the slide; Figure 25 6 is a top plan showing one of the bearings and parts carried thereby; Figure 7 is a sectional detail showing a portion of the door and parts of the guide; Figure 8 is a sectional detail showing the means whereby 30 the device may be rendered inoperative, when desired.

The numeral 1 marks a door frame whereunto a screen door, or other door, is hinged as shown at 3. The door 2 carries a guide 35 which is a composite structure, the guide comprising a U-shaped frame 4 which projects forwardly from the door 2, the frame comprising side arms 5 and a forward end member 6, the parts 5 and 6 being supplied 40 with continuous bottom flanges 7, and the side arms 5 being provided with top flanges 8, the flanges 8 terminating short of the end member 6 and being inclined upwardly, as they extend forwardly, Figure 2 being noted 45 at this point. The side arms 5 of the frame 4 are provided at their rear ends with inwardly projecting ears 9 abutting against the forward surface of the door 2. The guide comprises bars 10, alined with the side 50 arms 5 of the frame 4 and extended rearwardly from the door 2, the bars 10 having upstanding flanges 11. The bars 10 are provided at their forward ends with inwardly 55 extended ears 12. Securing members 14 pass

through the door 2 and engage the ears 9 55 and 12, the frame 4 and the bars 10 thus being held on the door 2.

A loop-shaped slide 15 is mounted for reciprocation transversely of the door 2, within the guide above described. The slide 15 60 includes a U-shaped member comprising a rear bar 16 and forwardly extended side pieces 17 having reduced ends 18 passing through the end of a head 19, the ends 18 of the side pieces 17 carrying cotter pins 20 or 65 the like, which hold the head 19 in place. The head 19 has cam edges 22 defining a rearwardly extended pointed nose 23.

A lower bearing 24 is mounted on the door 2. Shafts 25 and 26 are journaled at 70 their lower ends in the bracket 24, and are so mounted therein that they can swing inwardly and outwardly, toward and away from the door 2—a statement which will be better understood as the description proceeds. The shafts 25 and 26 carry lateral wings 27. An upper bearing 28 is secured to the door 2 and is provided with slots 29 which are elongated in a direction transverse to the door 2, the shafts 25 and 26 being journaled in the slots 29. The bearing 28 carries a forwardly extended projection 30. The shaft 25 has a forwardly extended arm 31, the shaft 26 having a forwardly extended arm 32, the arms being crossed upon 85 each other as at 33, adjacent to their forward ends. At their forward ends, the arms 31 and 32 have upstanding fingers 34 whereon rollers 35 are journaled, the rollers being disposed on opposite sides of the nose 23 on the head 19 of the slide 15. The shafts 25 and 26 have laterally extended crank arms 36. Retractile springs 37 are connected to the crank arms 36 and to the door 2.

The device includes a releasable catch, 90 adapted to cooperate with the rear bar 16 of the slide 15, the catch including depending compressible brackets 38 secured to the upper portion of the door frame 1, and located to the rear of the door 2, as shown in Figure 2. The brackets 38 are connected by a draw bolt 39 forming a shaft whereon a toothed wheel 40 is journaled, concaved compressible friction disks 41 being mounted on the bolt or shaft 39 and being interposed between the wheel 40 and the brackets 38. The construction of the releasable catch is such, obviously, that although 100 105

the wheel 40 will not rotate readily, it will rotate when a sufficient force is applied thereto.

Let it be supposed that the door 2 is closed as shown in Figure 2, the parts of the device being arranged as depicted in Figure 3, the rear bar 16 of the slide 15 being engaged with the toothed wheel 40. When the door is swung to an open position, the slide 15 is retained at first by the catch 38, the parts 17 of the slide moving in the openings 21 which are formed in the ears 9 and 12, and in the door 2. The nose 23 on the member 19 of the slide enters between the rollers 35 on the arms 31 and 32 of the shafts 25 and 26, the shafts being rotated, and the wings 27 swinging outwardly, away from the door, until the wings come together, the rollers 35 riding on the cam edges 22. The wings 27 are foraminous, and air can pass through them readily. The result is that the flies on the wings are held on the wings, and are crushed between the wings when the wings come together. As the wings 27 swing away from the door 2, the crank arms 36 on the shafts 25 and 26 put the springs 37 under tension. The arm 31 on the shaft 25 at length comes into contact with the projection 30 on the bearing 28, the shaft 25 being swung forwardly at its upper end, away from the door. The shaft 25 engages the arm 32 on the shaft 26 and carries the shaft 26 forwardly at its upper end, away from the door, the shafts 25 and 26 moving outwardly in the slots 29. Owing to the fact that the arms 31 and 32 are crossed, as shown at 33, the aforesaid movement of the shafts is necessary in order that the wings 27 may come together and crush the flies. Further, because the shafts are swung outwardly as aforesaid, the springs 37 are put under additional tension and are rendered peculiarly efficient for closing the wings 27 against the door 2 as hereinafter explained, the wings closing so quickly against the door that flies cannot light either on the door or on the inner surfaces of the wings. The flies light on the outer surfaces of the wings, when the wings are in the position shown in Figure 1, and, consequently, the flies are crushed between the wings, when the wings come together.

The end of the nose 23 on the bar 19 ultimately comes into contact with the upstanding portion of the upper bearing 28, and, then, the slide 15 moves forwardly for an instant with the door 2, the wheel 40 being rotated, and the rear bar 16 of the slide being detached from the wheel. Thereupon the springs 37 react, and cause the shafts 25 to be rotated, the shafts moving backwardly in the slots 29, into parallelism with the door 2, and the wings being closed against the door. When the shafts 25 and 26 are rotated by the springs 37, as aforesaid,

said, the arms 31 and 32 on the shafts swing into the position shown in Figure 3, the rollers 35 riding toward each other on the cam edges 22 of the bar 19 of the slide 15 and advancing the slide into the position 70 shown in Figure 3.

When the door 2 is swung to a closed position, the rear bar 16 of the slide 15 rides over one of the teeth of the wheel 40, and engages with the said tooth, and slide 15 75 tilting vertically on the door 2 and on the ears 9 and 12, to permit the rear bar 16 to engage with the said tooth of the wheel 40, it being observed, referring to Figure 7, that the openings 21 in the ears 9 and 12 and in 80 the door 2 are large enough to receive the side pieces 17 of the slide 15 somewhat loosely.

A hook 72 or like retainer, is pivoted on the door 2, and is adapted to be engaged 85 with the rear bar of the slide 15, as shown in Figure 8. The slide, then, will be held in the tilted position of Figure 8, clear of the wheel 40, the wings 27 remaining in 90 place on the door. The arrangement of parts shown in Figure 8 is such that the device may be set so that it will not operate, to crush the flies when the door is opened.

Having thus described the invention, what is claimed is:

1. In a device of the class described, a frame; a door hinged to the frame; panels mounted to swing on the door; a member movable on the door; means for connecting said member operatively with the panels to swing the panels away from the door and together when the door is opened and when said member is held against movement with the door; means on the frame for holding said member against movement with the door when the door is opened, the holding means being automatically releasable from said member after the door has been opened a predetermined amount; and spring means for swinging the panels toward the door and for advancing the movable member with respect to the door after said member has been released from the holding means.

2. In a device of the class described, a frame; a door hinged to the frame; shafts journaled on the door and having arms; panels carried by the shafts; a slide mounted to reciprocate on the door and cooperating with the arms to swing the panels away from the door, and together, when the door is opened and when the slide is held against movement with the door; automatically releasable means on the frame for holding the slide when the door is opened; and spring means for swinging the panels toward the door and for advancing the slide with respect to the door when the slide is released.

3. In a device of the class described, a frame; a door hinged to the frame; shafts journaled on the door and having crossed

arms; panels carried by the shafts; a slide mounted to reciprocate on the door and including a part adapted to enter between the outer ends of the arms thereby to swing the panels away from the door, and together when the door is opened and when the slide is held against movement with the door; automatically releasable means on the frame for holding the slide when the door is opened; and spring means for swinging the panels toward the door and for advancing the slide with respect to the door when the slide is released.

4. In a device of the class described, a frame; a door hinged to the frame; shafts mounted on the door to rotate thereon and to swing toward and away from the door, the shafts having arms; panels carried by the shafts; a slide mounted to reciprocate on the door and cooperating with the arm to

swing the panels away from the door, and together when the door is opened and when the slide is held against movement with the door; means on the frame for holding the slide releasably when the door is opened; 25 spring means for swinging the panels toward the door and for advancing the slide when the slide is released; and a projection on the door across which one arm is fulcrumed, when the door is opened, thereby 30 to swing the shaft from the door and to permit the panels to come together.

In testimony that I claim the foregoing as my own, I have hereto affixed my signature in the presence of two witnesses.
